UNITED STATES PATENT OFFICE.

MICHAEL W. MCARDLE, OF CHICAGO, ILLINOIS.

DESIGN FOR AN ELECTRIC HEATER.

Application filed October 24, 1928. Serial No. 28,615. Term of patent 14 years.

To all whom it may concern:

Be it known that I, MICHAEL W. MCARDLE, a citizen of the United States, residing at Chicago, in the county of Cook and State of Illinois, have invented a new, original, and ornamental Design for Electric Heater, of which the following is a specification, reference being had to the accompanying drawings, forming a part thereof.

In the drawing:

Figure 1 is a front elevation of an electric heater embodying my new design.

Figure 2 is a side elevation.

I claim:

The ornamental design for an electric heater substantially as shown.

In testimony whereof, I have hereunto set my hand this 22nd day of October, 1928.

MICHAEL W. MCARDLE.
